Primary Examiner — Jonathan J Han(74) *Attorney, Agent, or Firm* — Volpe Koenig(57) **CLAIM**

The ornamental design for a shoe as shown and described.

DESCRIPTION

FIG. 1 is a left side elevational view of a first embodiment of a shoe in accordance with my design; and
 FIG. 2 is a right side elevational view thereof;
 FIG. 3 is a left side elevational view of a second embodiment of a shoe in accordance with my design; and,
 FIG. 4 is a right side elevational view of a third embodiment of a shoe in accordance with my design.
 The broken lines represent portions of the shoe in which the design is embodied that form no part of the claimed design.
